UNITED STATES PATENT OFFICE.

WILLIAM E. SHORE, OF NEW YORK, N. Y.

THERMOSTATIC CONTROL FOR OIL BURNERS.

Application filed July 31, 1922. Serial No. 578,648.

To all whom it may concern:

Be it known that I, WILLIAM E. SHORE, a subject of the King of Great Britain, and resident of the city and State of New York, 5 in the United States of America, have invented certain new and useful Improvements in a Thermostatic Control for Oil Burners, described in the following specification and illustrated in the accompanying 10 drawings, that form part of the same.

The principal objects of this invention are, to effect a positive control of a supply of fuel to a burner, whereby the operation of the supply will be completely suspended in 15 the event of the flame being extinguished.

A further object is to devise a control which may be interposed directly into the path of the flame from the burner, and further to provide means for maintaining a 20 continuous circulation of a heat distributing fluid through the portion of the device subjected to the flames.

The principal feature of the invention consists in the arrangement of a tubular 25 conduit connected with a thermostatic control in the path of the flame emanating from a burner and connecting said conduit with a fluid supply in such a manner that a continuous circulation of fluid may be maintained therethrough.

The drawing is an elevational view of a heating plant showing the application of my invention thereto.

In the form of the device illustrated here- 35 in a boiler 1 is shown arranged above a firebox 2 and a circular air register 3 is arranged in front of the opening 4. Within the register 3 is supported the burner 5 which is connected to the fuel supply tube 40 6 leading to the fuel supply mechanism. The burner projects a flame into the fire-box beneath the boiler 1.

A conduit is formed by an arrangement of pipes formed into a loop 8 arranged within 45 the fire-box in alignment with the vertical centre line of the register so that the flame from the burner impinges directly upon the loop, imparting thereto the full heat of the flame. The lower end of the loop is connected by a branch pipe 9 to the boiler 1 at a point adjacent to its bottom and the upper end is connected by a pipe 10 to the front of the boiler at a point close to high water 50 level.

The heat of the flame impinging against 55 the loop 8 heats the water in said loop causing it to travel upwardly and discharge through the pipe 10 into the boiler drawing a cooler supply through the pipe 9 to the bottom of the loop.

This system of fluid circulation through a pipe interposed in the path of the flame from the burner ensures the maintenance of a constant temperature of fluid in the pipe when the burner is projecting a flame but 65 if the flame is extinguished the temperature in the circulating loop will immediately drop as its lower end is connected with the coolest portion of the water system.

A suitable thermostat may be arranged 70 within the loop 8 and the pipe 10 is preferably provided with an extension 11 from which an operating connector 12 from the thermostat extends to a control board 13. This thermostatic connector is adapted to 75 cut out the electric current being supplied to the electric motor for driving the fuel supply mechanism or to otherwise arrest the fuel supply, consequently when the flame is extinguished the thermostat operates to arrest 80 the operation of the burner and discontinues the supply of fuel. Suitable manually operable means is provided for enabling the starting of the fuel supply.

This system of control is extremely simple 85 and maintains a condition of thermostat control which will be very constant as the heat of the flame will maintain the water flowing through the conduit much higher than the temperature of the water in the main system and at a temperature which will maintain the operation of the fuel supply but upon the flame being extinguished the temperature in the conduit will immediately be reduced to a point which will cause the operation of the thermostatic device. The pipe arranged in the path of the flame will be adequately protected against burning by the constant flow of fluid therethrough.

What I claim as my invention is:—

1. A thermostatic control for oil burners, comprising, a burner, a main reservoir, a conduit independent of the circulating system of said reservoir and leading from a low point of said reservoir and returning to a high point and passing contiguous to the flame of the burner, and a thermostatic device controlled by the temperature of the

fluid flowing in said conduit adapted to cut off the fuel supply to the burner in the event of the flame being extinguished.

2. In a thermostatic control for oil burners, the combination with a boiler and a burner directly heating said boiler, of a tube leading from the lower portion of said boiler independent of the boiler circulating system and passing contiguous to the path of the flame of the burner and extending upwardly to the boiler and discharging thereinto at a point above the level of its supply, a thermostat arranged in said tube and a thermostat operated member controlled by the operation of the thermostat affected by the temperature of the fluid flow-

ing through said tube adapted to shut off the flow of fuel to the burner following the extinction of the flame.

3. In a thermostatic control for oil burners, the combination with a boiler and a burner for heating the same, of a conduit connected with said boiler and adapted to circulate a portion of the fluid contained in said boiler independent of the boiler circulation, said conduit being maintained at a high temperature by said burner, and thermostatic means responding to a drop in the maintained temperature of said conduit for cutting off the supply of fuel to said burner.

WILLIAM E. SHORE.
